(57) **CLAIM**

The ornamental design for a shave cup, as shown and described.

DESCRIPTION

FIG. 1 is a top perspective view of a first embodiment of the shave cup;

FIG. 2 is an elevation view of the embodiment of FIG. 1; FIG. 3 is a top plan view of the embodiment of FIG. 1; FIG. 4 is a bottom plan view of the embodiment of FIG. 1; FIG. 5 is a top perspective view of a second embodiment of the shave cup;

FIG. 6 is an elevation view of the embodiment of FIG. 5; FIG. 7 is a top plan view of the embodiment of FIG. 5; and, FIG. 8 is a bottom plan view of the embodiment of FIG. 5. The evenly spaced broken lines shown in the figures represent portions of the shave cup that form no part of the claimed design.
